TRACK FOR USE IN FURNACES

Application filed February 4, 1929. Serial No. 337,481.

This invention relates to improvements in work-supporting skids or tracks for use in industrial furnaces. It is an object of the invention to provide 5 a track which shall be so constructed as to permit proper cooling thereof with minimum abstraction of heat from the heating chamber. Another object is to provide a track of such construction that the work-supporting 10 rail thereof may expand lengthwise of its cooling element without causing upward bowing of the track as a whole due to the unequal expansion between the rail and its cooling element. Other objects will more fully appear 15 hereinafter.

In accordance with this invention, the track includes a tube through which cooling water may be passed and a longitudinally extending rail secured to the tube in a manner to permit 20 longitudinal expansion of the rail with respect to the tube, the rail consisting of individual sections each of which is secured between its ends to the tube as by a weld. To minimize the abstraction of heat from the 25 heating chamber, the exposed portion of the tube is covered with refractory insulating material, the material being held in place in a novel manner hereinafter described.

For a more complete understanding of the 30 invention, reference is made to the detailed description taken in connection with the accompanying drawings wherein the preferred construction of the track is shown.

Referring to the drawings, Fig. 1 is a plan view of a furnace showing the work-supporting tracks or skids extending lengthwise thereof, the top of the furnace being removed.

Fig. 2 is a transverse cross section of the 40 furnace shown in Fig. 1, an ingot or billet being shown supported on the tracks.

Fig. 3 is a longitudinal section of the improved track with a fragment in elevation, the view being on an enlarged scale.

Fig. 4 is a transverse section of the track 45 shown in Fig. 4, the inner or water supply being omitted.

Fig. 5 is a perspective view of the skid with 50 part of the heat-insulating jacket broken away to show the lattice construction which

serves to hold the jacket in place about the tube.

Fig. 6 is a plan view of a modified form of expansion joint for the track.

In the drawings, 7 indicates the side walls 55 of a furnace, 8 the roof and 9 the bed or floor thereof enclosing a heating chamber H. Openings O, O' at opposite ends of the furnace provide for ingress and egress of the work such as ingots or billets W to be heated. The tracks are generally indicated at 10 and may be supported in any suitable manner as 60 on a series of cross supports 11 supported by the furnace side walls and central piers 12.

Referring now more particularly to Figs. 65 3, 4, and 5, each track consists of a tube 15 on which is supported a rail 16 consisting of a series of rail sections separated from each other by expansion joints 17 of any preferred type as for example gaps 17 as shown in Figs. 3 and 5 or sliding joints 17' as shown in Fig. 6. The undersurface of each rail section conforms with that of the tube in order 70 to form a good thermal connection therebetween. Each rail section is held in position on the tube by a relatively short weld 18 between the ends of the section. The weld is made sufficiently long to firmly secure the rail section to the tube and is preferably made

at the marginal edge between the rail section 75 and tube as will be readily understood by reference to Fig. 3. In the preferred construction of tracks, the tube 15 will be round and hence the seat on the underside of the rail

will be of arcuate form, this form of seat obviously assisting in keeping the rail longitudinally aligned with the axis of the tube. It will now be readily appreciated that those 80 portions of the rail sections on either side of the weld are free to expand longitudinally of the tube and that by reason of said construction, there will be little if any tendency of the track as a whole to bow out of alignment

because of the tube being relatively cooler 85 than the rail.

The manner of securing the heat-insulating 90 jacket about the exposed portion of tube 15 will now be described. The jacket itself is indicated at 20 and encases the tube from one side to the other of the rail, the top or 100

work contacting portion thereof being left bare. The anchorage for the jacket consists of a lattice through the meshes of which plastic refractory material may be forced into contact with the tube. The lattice itself may be of any suitable form. In order to space the lattice from the tube there is provided a series of split rings 21 the ends of which seat in holes or depressions formed in the sides of the rail, the lattice being preferably spot welded to the rings. To more securely hold the lattice and split rings in place, there is spirally wound about the lattice work a wire 22 which passes through a series of transverse holes in the rail. The jacket is, of course, made sufficiently thick to completely embed the lattice. It is preferred to leave the surface of the jacket relatively rough since a smooth surface tends to cause cracks when drying.

The rail 16 will preferably consist of a heat-resisting alloy as will also the anchorage for the insulating jacket. Since the rail is in good thermal relation with the tube by reason of the close contact therebetween, the heat absorbed by the rail will be readily taken up by the cooling water in the tube. The water may be circulated through the tube 15 in any preferred or suitable manner as for example by a tube 23 positioned within the tube 15.

Various changes in construction may obviously be made without departing from the spirit of the invention, and no limitations are intended except as may be defined by the appended claims.

What is claimed is:

1. A track for use in furnaces comprising a rail, a support for the rail having a passage for cooling medium extending lengthwise thereof, and a heat-insulating jacket encasing the rail except for the work contacting portion thereof.
2. A track for use in furnaces comprising a cooling tube, a rail extending axially of the tube in thermal connection therewith, and a heat-insulating jacket encasing the exposed portion of the tube.
3. A track for use in furnaces comprising a cooling tube and a rail extending lengthwise of and in thermal connection with the tube, the continuity of the rail being interrupted by expansion joints, and heat insulating material covering the adjoining portions of the tube and rail.
4. A track for use in furnaces comprising a tube and a rail extending lengthwise of and in thermal connection with the tube, the continuity of the rail being interrupted by expansion joints, and the rail sections intermediate their ends being fixedly secured to the tube.
5. A track for use in furnaces comprising a tube, a rail extending lengthwise of and in thermal connection with the tube, the con-

tinuity of the rail being interrupted by expansion joints, and the rail sections intermediate their ends being welded to the tube.

6. A track for use in furnaces comprising a cooling tube, a rail extending axially of the tube in thermal connection therewith, a lattice spaced from and surrounding the tube except where it is in thermal connection with the rail, and a heat insulator secured about the tube by said lattice.

7. A track for use in furnaces comprising a cooling tube, a rail extending axially of the tube in thermal connection therewith, a lattice curved about the tube, means for securing the lattice to the rail, and a heat-insulating material anchored to the lattice.

8. A track for use in furnaces comprising a rail, a cooling tube on which the rail is seated, a series of split rings the ends of which are seated in the rail, a lattice secured to said rings, and a refractory body in which the lattice is embedded.

In testimony whereof we affix our signatures.

LLOYD J. STANBERY.
